UNITED STATES PATENT OFFICE.

HARRY W. WEYMAN, OF PHILADELPHIA, PENNSYLVANIA.

DESIGN FOR A MANDOLUTE.

43,684.

Specification for Design.

Patented Mar. 4, 1913.

Application filed July 27, 1912. Serial No. 711,924. Term of patent 14 years.

To all whom it may concern:

Be it known that I, HARRY W. WEYMAN, a citizen of the United States, residing at Philadelphia, county of Philadelphia, and State of Pennsylvania, have invented a new, original, and ornamental Design for a Mandolute, of which the following is a specification, reference being had to the accompanying drawing, forming a part thereof.

Figure 1, is a plan view of a musical in-

strument. Fig. 2, is an edge view thereof, and Fig. 3, is an end view thereof.

I claim:

The ornamental design for a mandolute as shown.

HARRY W. WEYMAN.

Witnesses:

E. C. MULLEN,
M. C. Fox.
